UNITED STATES PATENT OFFICE.

ANITA K. TANQUARY, OF LOS ANGELES, CALIFORNIA.

HOLDER.

Application filed February 9, 1926. Serial No. 87,014.

This invention has to do generally with kitchen utensils, and is more particularly concerned with a device for holding articles such as vegetables, fruit or nuts when they are to be grated. The invention considered in its broader aspects, however, need not necessarily be limited to such specific application, since it may be applied with equal advantage to devices adapted to hold articles for other purposes.

When grating vegetables or the like, especially if the vegetables are slippery or are so short or of such contour that they may not be firmly grasped, it is a common occurrence for the one holding the article to have their fingers slip onto the rough, sharp surface of the grater, with most painful results. Knowing the danger of such occurrences, one often wastes considerable food material by failing to grate it beyond the point where it may be firmly gripped.

Therefore, it is the general object of my invention to provide a device whereby vegetables or the like may be gripped firmly, irrespective of their contour and facial characteristics, within reasonable limits, the holder protecting the user's hand by preventing it from coming into contact with the grater, no matter how far down the article may have been grated. The device includes releasable clamp means which are operable from the rear of the shield plate, which clamp is adapted to grasp the article firmly even though it be very short. The clamp is so devised that it operates without requiring any considerable amount of conscious effort on the part of the operator, the natural tendency to squeeze the fingers together in grasping the handle of the device serving to move the clamp into operative position.

It is also among the objects of the invention to provide a device of the character described which will be light, sturdy and comparatively simple, whereby it may stand up under service conditions and yet be produced at a cost sufficiently low to warrant its common use.

Other features of novelty and objects of the invention will be made apparent in connection with the following detailed description, reference being had to the accompanying drawings, in which:

Fig. 1 is a perspective view showing a vegetable held in a device embodying my invention, and being applied to a grater;

Fig. 2 is a view of the front face of the device;

Fig. 3 is a section on line 3—3 of Fig. 2; and

Fig. 4 is a section on line 4—4 of Fig. 3. 60

In the drawings, numeral 10 designates a face or shield plate which is substantially rectangular in outline, though its upper corners may be cut off as at 11. The shield plate is provided with an aperture 12, preferably circular, whereby an article, such as a carrot C (Fig. 1) may be thrust through the plate aperture to extend beyond both the front face 13 and rear face 14 of said plate. 65

The two opposite side edges 15 of plate 10 are turned over to provide guideways 16 which are adapted to receive the opposite edges of a substantially rectangular slide plate 17 which makes up a part of a movable clamp element or jaw generally designated 70 by numeral 18 and arranged at the lower side of aperture 12. The lower edge 19 of plate 10 is turned up to provide a channel 20 for the reception of the lower edge of slide plate 17, and forms a stop limiting the extent of sliding movement of plate 17 in one direction. 75

The upper edge of slide plate 17 is preferably cut away to provide an arcuate notch 21 which preferably has the same radius of curvature as aperture 12 and is in alignment with the lower part of said aperture when the slide plate is in its lowermost position. Turned outwardly from slide plate 17 and away from shield plate 10 is a lip 22 which 80 preferably follows the curvature of notch 21, so it may be described as a lip of arcuate transverse cross section, the axis of the lip being substantially coincident with the axis of aperture 12 when plate 17 is in its lowermost position. 85

Preferably, the upper face of lip 22 is roughened to give it good gripping characteristics. This roughening may be done conveniently and well by punching the lip 100 through from the bottom to provide upstanding, hollow projections or teeth 23, so the upper face of the lip has the characteristics of a grater. A finger grip 24 is provided on member 18, whereby said member 105 may be slid over shield plate 10 in a manner to traverse aperture 12. This grip 24 may be made conveniently in the form of a finger ring secured by solder or any other suitable means to the slide plate at 25. 110

Preferably, the ring is also soldered to the under face of lip 22 as at 26, this form of securement not only allowing the application of finger pressure directly to the under face of the lip, but also providing a brace between the lip and slide plate, that is, a brace for the angle formed by turning the lip outwardly from the plate. Ring 24 is preferably located in the vertical axial plane of aperture 12.

A handle for the device is provided in the form of a gripping bar 27 which is spaced from the rear face of plate 10, the ends 28 of said bar being bent inwardly and terminally secured at 29 to said plate. The bent ends 28 are spaced apart sufficiently to allow the entrance therebetween of the operator's fingers when bar 27 is grasped, and the bent ends prevent the fingers from sliding over the upper and lower ends of the shield plate and onto the serrated face of grater G (Fig. 1). In other words, the handle serves as a hand guard as well as means for holding and manipulating the device.

25 A stationary clamp element or jaw is provided at the side of aperture 12 opposite to that at which slidable clamp member 18 is located; or the edge of the plate which defines said opposite side of the aperture may 30 be considered a stationary jaw or clamp element. This stationary clamp element may be in the form of a cross piece 30 which is preferably of arcuate cross section as shown in Fig. 4, and extends between and is terminally secured to the rear face of plate 10 and the inner face of handle bar 27. Clamp element 30 is preferably disposed diametrically opposite finger ring 24, its curvature being such that lip 22 may be slid up into close 35 proximity therewith so as to grip relatively thin articles therebetween. The lower face 31 of clamp element 30 is preferably in line with aperture 12 at a point diametrically opposite ring 24 and this under face is preferably roughened as at 32 in a manner similar to that described in connection with lip 22, projections 32 extending downwardly sufficiently far to insure that articles thrust 40 through aperture 12 may be gripped thereby.

Cross piece 30 extends longitudinally parallel to the axis of lip 32, and serves as a brace and tie between plate 10 and handle 27. It also provides a rest for the thumb of the operator, as will be evident from a consideration of Fig. 1.

In using the device, plate 17 is lowered sufficiently to open up aperture 12 to such an extent that a vegetable or other article such as carrot C may be thrust approximately into the position of Fig. 1. By then resting the thumb upon cross piece or stationary clamp element 30, inserting one of the fingers through ring 24, and squeezing the thumb 60 and finger together as is natural in tightly

gripping any holding device, plate 17 is slid upwardly or caused to traverse aperture 12 in a manner to grip the end of the carrot tightly between clamp elements 22 and 30. It is to be noted that plate 17 is movable into 70 and out of clamping position through a plane substantially parallel with the plane of plate 10. While it is unimportant as to which finger is inserted through ring 24, it is convenient to use the second finger for this 75 purpose, so the forefinger may be used for exerting longitudinal pressure against the article to back it up during grating operations or to project the article outwardly through aperture 12 when the clamp is 80 loosened thereabout, as the article becomes shorter by reason of the grating operation. In other words, the forefinger may be used to adjust the article longitudinally when the clamp is somewhat loosened. 85

It will be evident that with the carrot thus held between the clamp elements that the operator may proceed with dispatch to grate that end of the article which extends outwardly beyond front face 13 of plate 10, and that the shield plate fully protects the hand, and more particularly the knuckles, by preventing them from coming into contact with the grater, the bent over ends of the handle serving also as a guard, as previously described.

It will be understood the drawings and description are to be considered merely as illustrative of and not restrictive on the broader claims appended hereto, for various 100 changes in design, structure and arrangement may be made without departing from the spirit and scope of said claims.

I claim:

1. In a device for holding an article to be 105 grated, a shield plate having an aperture through which the article is adapted to be thrust so it extends beyond both the front and rear face thereof, a handle extending from the rear face of the plate, and a releasable, two-jaw clamp on the plate positioned to engage the article at the rear of the plate and hold it firmly thereto one of said jaws being slidable over the plate in a manner to traverse the aperture. 110

2. In a device for holding an article to be 115 grated, a shield plate having an aperture through which the article is adapted to be thrust so it extends beyond both the front and rear face thereof, a handle extending from the rear face of the plate, and a releasable clamp on the plate positioned to engage the article at the rear of the plate and hold it firmly thereto; said handle embodying a bar spaced from the rear face of the 120 plate and having its end bent inwardly and secured to said plate, the spacing of said arms being sufficient to receive a hand therebetween when the bar is grasped.

3. In a device for holding an article to 125

be grated, a shield plate having an aperture through which the article is adapted to be thrust so it extends beyond both the front and rear face thereof, a handle extending from the rear face of the plate, clamp members on the plate at opposite sides of the aperture, one of the members being slidable over the plate towards and away from the opposite clamp member, and a finger grip 5 on said movable member whereby the slid-
10 able member is adapted to be moved by finger pressure.

4. In a device for holding an article to be grated, a shield plate having an aperture through which the article is adapted to be thrust so it extends beyond both the front and rear face thereof, a handle extending from the rear face of the plate, a stationary clamp member on the shield plate 15 at one side of the aperture, and a slid-
20 able clamp member on the shield plate at the opposite side of the aperture and adapted to be slid towards and away from the stationary member, said slid-
25 able member embodying a substantially rectangular slide plate in facial engagement with the rear face of the shield plate and having two of its opposite edges disposed in guideways provided on the shield plate, and a transverse lip 30 on the slide plate turned away from the shield plate and facing the first mentioned clamp member.

5. In a device for holding an article to be grated, a shield plate having an aperture through which the article is adapted to be thrust so it extends beyond both the front and rear face thereof, a handle extending from the rear face of the plate, a clamp member on the shield plate at one side of the aperture, and a slid-
40 able clamp member on the shield plate at the opposite side of the aperture and adapted to be slid towards and away from the first mentioned clamp member, said slid-
45 able member embodying a substantially rectangular slide plate in facial engagement with the rear face of the shield plate and having two of its opposite edges disposed in guideways provided on the shield plate, and a transverse lip on the 50 slide plate turned away from the shield plate and facing the first mentioned clamp member.

6. In a device for holding an article to be grated, a shield plate having an aperture

through which the article is adapted to be thrust so it extends beyond both the front and rear face thereof, a handle extending from the rear face of the plate, a clamp member on the shield plate at one side of the aperture, and a slid-
55 able clamp member on the shield plate at the opposite side of the aperture and adapted to be slid towards and away from the first mentioned clamp member, said slid-
60 able member embodying a substantially rectangular slide plate in facial engagement with the rear face of the shield plate and having two of its opposite edges disposed in guideways provided on the shield plate, a transverse lip on the slide plate turned away from the shield plate and facing the first mentioned clamp member, and a finger grip 65 on said slide plate.

7. In a device for holding an article to be grated, a shield plate having an aperture through which the article is adapted to be thrust so it extends beyond both the front and rear face thereof, a handle extending from the rear face of the plate, a stationary clamp member on the shield plate at one side of the aperture, and a slid-
75 able clamp member on the shield plate at the opposite side of the aperture and adapted to be slid towards and away from the stationary member, said slid-
80 able member embodying a substantially rectangular slide plate in facial engagement with the rear face of the shield plate and having two of its opposite edges disposed in guideways provided on the shield plate, a transverse lip on the slide plate turned away from the shield plate and facing the stationary clamp member, and a finger ring secured to said slide plate 85 and to the lip.

8. In a device for holding an article to be grated, a shield plate having an aperture through which the article is adapted to be thrust so it extends beyond both the front and rear face thereof, and a releasable clamp on the plate positioned to engage the article at the rear of the plate and hold it firmly thereto, said clamp embodying an element which is movable into and out of clamping position through a plane substantially parallel with the plane of the plate.

In witness that I claim the foregoing 95 I have hereunto subscribed my name this 100 28 day of January, 1926.

ANITA K. TANQUARY.
